UNITED STATES PATENT OFFICE.

FRANÇOIS JURICINEC, OF PARIS, FRANCE, ASSIGNOR TO LAURENT JURICINEC, OF PITTSBURGH, PENNSYLVANIA.

POLISHING MACHINE CHIEFLY FOR SANDPAPERING OR VARNISHING WITH A PAD THE SURFACE OF MATERIALS SUCH AS WOOD, MARBLE, STONE.

Application filed May 11, 1925, Serial No. 29,603, and in France July 9, 1924.

The present invention relates to certain new and useful improvements in polishing machines chiefly for sand papering or varnishing with a pad the surface of material such as wood, marble, and stone, and the objects and features of advantage will become apparent as the description proceeds.

An embodiment of a wood sand papering machine is described hereinbelow, by way of example and shown on appended drawings together with a device for securing the tool specially adapted for polishing marble with emery wheels. An embodiment of a pad varnishing machine is also described.

Fig. 1 is a general front view of the sand papering machine with a sand disc for polishing wood.

Fig. 2 is on a smaller scale a side view of the machine.

Figs. 3 and 4 are, at another scale, a plan view and a side view of the end of the motor shaft with its disc.

Fig. 5 is a perspective view of the square tenon serving to secure the disc.

Figs. 6 and 7 are a partially sectional side view and a plan view from underneath of the device for securing an emery wheel to this machine.

Figs. 8, 9 and 10 show, in side and front view the whole pad varnishing machine and in vertical cross-section the end of the motor shaft of this machine with its pad.

The machine shown on Figs. 1, 2, 3 and 4 comprises essentially a frame with two uprights 1 and 2 held together by the bars 3 and 4 at their upper part and by the supporting bar 5. At their top part the uprights are provided with two jaws opposite one another and between which an electric motor can be inserted. The motor controls a vertical shaft 11 connected with the motor shaft by means of a conical coupling sleeve 10. The shaft 11 ends with a ball 12 inserted between a lower half socket 13 and a higher half socket 14. The higher half socket is screwed into the half socket 13 so as to provide for a very precise adjustment of the play between the ball and its socket. Recesses 15 allow the screwing and unscrewing of part 14 in part 13. A stop screw 16 passing through part 14 can be screwed in a certain number of holes 17 previously provided in the lower half socket 13.

This lower half socket 13 forms a cylindrical plate 18 the lower part of which holds a square tube 19 (Fig. 5) the walls of which are comparatively thin and each side 20 of which has two notches 21, 22 which make it independent from the angle posts 23, 24. The sides such as 20 act as springs. This tubular square tenon 19 can engage (Fig. 1) in a square wooden block 25 which is the working disc. This block receives at its lower part about twenty sand paper sheets 26 the edges of which are folded over the sides of the disc and are secured between the plates 27, 28 drawn together by means of the threaded rods 29 provided with winged nuts 30.

Over the lower half socket 13 and formed integrally therewith, is the gear wheel 31 with a vertical toothwork. On the extremity of the shaft 11 a sleeve 32 is slidably mounted by means of the key 33. This sleeve can be fastened by the stop screw 34. The lower part of the sleeve 32 bears a gear wheel 36 meshing with the gear wheel 31.

Recesses 38 are provided in the supporting bar 5 for the reception of parts 42 serving as a nut for screws 39 having the threaded portion 40 and the winged portion 41. The parts 42 are suitably fixed in the recesses.

The lower bearing of motor shaft supports a bell-shaped part 43 (Fig. 2) open at its bottom and stopping slightly above the surface 44. The whirlwind produced by the rotation of the tool projects the dust against the walls of the bell-shaped part.

The working of the machine is the following: It stands on the support formed on one hand by the frame 1, 2 and on the other hand by the shaft 11 and the disc 25 and therefore the electric motor being overhung, the working disc 25 presses strongly upon the surface 44 to polish. This disc bears completely upon the surface because of the ball and socket joint at the extremity of shaft 11. When the electric motor is actuated, the shaft 11 causes the rotation of the disc 25 by means of the gear wheels 31-36. By reason of the play of these parts, this rotation can take place whatever may be, between certain limits, the direction of the disc 25 with reference to the shaft 11. However, experience proves that for a satisfactory rotation of the disc without any

speed irregularities or vibrations the gear work 31—36 should have for each speed of the motor shaft, a predetermined play and that the ball 12 should also have a very slight play inside its socket. The devices which enable the play in the socket and in the gear work to be adjusted and which have been described hereinabove, allow this adjustment to be easily and speedily obtained.

As the work advances the sand paper sheets 24 wear out and are replaced. At the same time in order to prevent the disc 25 from inclining too much with reference to the shaft 11, the two adjusting screws 41 are turned so as to correspondingly move the small supporting bar 37. The sand papering of a wooden surface must be made with a series of sand papers of increasing fineness. The proper amount of sand paper sheets of each fineness is previously set on discs such as 25. When the first disc has finished its work, it is easily removed as it is secured only by the square tubular spring tenon and a fresh disc is put in its place.

The workman controls the work and pushes the machine successively on the different parts of the surface to polish and makes it act longer on those parts which require it. The machine is particularly apt for sand papering veneered wood, when the veneer is very thin and is not properly stuck against its support in all parts thereof. When the machine arrives on a part where the veneer is raised, it bears on this part only by its weight, as it does on any other part and the disc is inclined so as to bear normally on the veneer whereby all danger of breaking open the raised part of the veneer is avoided.

When the machine is intended for working a marble or stone or similar surface, it is necessary to replace the wooden disc 25 with its sand paper sheets 26 by a generally circular emery stone provided with a central square hole in its center. Such a stone is shown in 45 on Figs. 6 and 7. For securing quickly the stone, a plate 18 is used carrying a square projection 46 on its lower surface. This projection is tapped in its center and is split along its angles so as to form four elastic segments 47, 48, 49 and 50. The emery stone 45 shows, as stated, a central square hole of corresponding size which can engage over the square projection 46. In the tapped part of the projection is screwed a screw 51, conical head 52 of which enters the conical opening of the tapped part. When the screw is suitably screwed, the four sides of the square projection are slightly expanded and bear exactly against the sides of the square hole in the stone 45 which is thus securely held.

A varnishing machine of the same type is shown on Figs. 8, 9 and 10. On the end of shaft 11 is secured a hollow part 53 provided with a series of holes 54 and carrying

a pad of flock 55 held by the cloth 56 and the ring 57. This hollow part is secured to a tapped block 48 wherein is screwed a screw 59 projecting from the lower part of plate 18. The frame 1, 2 bears a reservoir 60 divided in three compartments, one of which contains alcohol and another varnish which are led into the hollow part 53 through the tubes 61, 62. The third compartment of the reservoir contains oil which can be led directly on to the surface to polish through the tube 63. In this case the frame 1, 2 is preferably provided at its lower part with a roller 64.

The working of this pad varnishing machine is the same as that of the sand papering machine. These machines differ only by the tool secured on the extremity of the shaft 11. The varnish and the alcohol flowing at a suitable rate arrive in the hollow part 53, pass through the holes 54 and moisten the pad 55. The cloth 56 lets a suitable amount of this liquid pass through it. The tube 63 allows a suitable quantity of oil to be poured over the surface to polish in front of the part to varnish. When it is necessary to change the pad either because it is worn out or because it is too saturated with alcohol or varnish, it can be done merely by unscrewing the hollow part 53 from the screw 59 and to screw another, hollow part in its place.

What I claim is:

1. A machine for polishing the surface of materials such as wood, marble and stone comprising a frame resting on the surface to be polished, a motor supported by said frame, a shaft operable by said motor and disposed perpendicularly to the surface to be polished, a ball at the extremity of the shaft, a socket cooperating with said ball and comprising a lower half-socket and an upper half socket at an adjustable height above the lower half socket, a gear wheel formed on the socket, a second gear wheel connected to the shaft and meshing loosely with the first gear wheel to provide a certain play between said gear wheels, and a working tool secured to the lower half-socket.

2. A machine for polishing the surface of materials such as wood, marble and stone comprising a frame adapted to rest on the surface to be polished, a motor supported by said frame, a shaft operatively associated with the motor and extending perpendicularly to the surface to be polished, a ball at the extremity of said shaft, a lower half socket under said ball, an upper half socket adjustably associated with the lower half socket, a gear wheel on the lower half socket, a second gear wheel on the motor shaft and meshing loosely with the first gear wheel to provide a certain play between both gear wheels, a working tool secured to the lower

half socket, and a means for adjusting the height of the frame.

3. A machine for polishing the surface of materials, such as wood, marble, and stone comprising a frame adapted to rest on the surface to be polished, a motor supported by said frame, a shaft operatively associated with the motor and disposed perpendicularly to the surface to be polished, a ball at the extremity of the said shaft, a socket associated with said ball and comprising a lower half socket and an upper half socket screwed in the lower half socket, a stop screw for the upper half socket, a gear wheel provided on the socket, a second gear wheel slidably mounted on the shaft and loosely meshing with the first gear wheel to provide a certain play between both the gear wheels, a stop screw for said second gear wheel, a working tool secured to the lower half socket, a supporting bar under the frame, and screws for adjusting the height of said bar.
4. A machine for polishing the surface of materials such as wood, marble and stone, comprising a frame adapted to rest on the surface to be polished, a motor supported by said frame, a shaft operatively associated with the motor and disposed perpendicularly to the surface to be polished, a ball at the extremity of the shaft, a socket cooperating with said ball and comprising a lower half socket and an upper half socket screwed in the lower half socket, a stop screw for the upper half socket, a gear wheel formed on the socket, a second gear wheel slidably mounted on the shaft and meshing loosely with the first gear wheel to provide a certain play between both gear wheels, a stop screw for said second gear wheel, a spring square tubular tenon projecting under the lower half socket, said tenon provided with longitudinal slots along the sides thereof, and a working tool provided with a square mortise for receiving said tenon.

In witness whereof I have hereunto set my hand.

FRANÇOIS JURICINEC.

mounted on the motor shaft and meshing loosely with the first gear wheel to provide a certain play between the gear wheels, a stop screw for said second gear wheel, a spring tenon projecting under the lower half socket, a working tool, said tool provided with a mortise for receiving said tenon, a supporting bar under the frame, and screws for adjusting the height of said supporting bar.

5. A machine for polishing the surface of materials such as wood, marble and stone, comprising a frame resting on the surface to be polished, a motor supported by the frame, a shaft operatively associated with the motor and disposed perpendicularly to the surface to be polished, a ball at the extremity of the shaft, a socket cooperating with said ball and comprising a lower half socket and an upper half socket screwed in the lower half socket, a stop screw for the upper half socket, a gear wheel on the socket, a second gear wheel slidably mounted on the motor shaft and meshing loosely with the first gear wheel to provide a certain play between both gear wheels, a stop screw for said second gear wheel, a spring square tubular tenon projecting under the lower half socket, said tenon provided with longitudinal slots along the sides thereof, and a working tool provided with a square mortise for receiving said tenon.
